BRAKE FOR TOY VEHICLES

Harold Frank Davis, Keene, N. H., assignor to
 Kingsbury Manufacturing Company, Keene,
 N. H., a corporation of New Hampshire

Application March 23, 1935, Serial No. 12,719

4 Claims. (Cl. 46—208)

The present invention relates to new and useful improvements in a braking device for a toy vehicle and more particularly to an improved braking device for a motor operated toy vehicle.

5 An object of the invention is to provide, in a motor operated toy vehicle, a braking device which is adapted to be moved into positive locking engagement with one of the gears in the driving train.

10 A further object of the invention is to provide, in a motor operated toy vehicle, a braking device which cooperates with one of the intermeshing driving gears to slow up the motor and to thereafter positively lock the gear against 15 movement.

15 A still further object of the invention is to provide, in a motor operated toy vehicle, a braking device which positively engages between the teeth of one of the intermeshing driving 20 gears at a point removed from the line along which the gears mesh.

25 A still further object of the invention is to provide, in a motor operated toy vehicle, a braking device which is slightly resilient and which first cooperates with one of the intermeshing driving gears to frictionally slow up the motor and which thereafter positively locks the gear against movement.

30 The above and other objects of the invention will in part be obvious and will be hereinafter more fully pointed out.

In the accompanying drawing—

Figure 1 is a side elevation showing an assembled toy vehicle;

35 Fig. 2 is a detail bottom plan view showing the rear driving wheels, spring motor and brake device;

40 Fig. 3 is a diagrammatic view showing the brake lever and gear with which it cooperates, and

Fig. 4 is a view, similar to Fig. 3, but showing the brake lever before it has locked the gear against rotation.

45 The invention will be described in detail, reference being had to the accompanying drawing wherein the invention is shown as applied to a toy automobile, although it is to be clearly understood that the invention may be applied to any type of toy vehicle. The body 10 of the 50 vehicle is shown as of the coupe type for purposes of illustration only. The body is supported by front wheels 11 and rear driving wheels 12. The rear wheels 12 are mounted on an axle 13 which extends through a housing 14. The 55 housing 14 is secured to the vehicle in any suit-

able manner and is provided with downwardly extending portions 15, 15a which support the axle 13. A spring motor of similar construction to that shown in the Rechel Patent No. 1,512,136, granted October 21, 1924, is mounted 5 within the housing 14 and is provided with a handle 16 by which the motor may be wound. The crown or driving gear 17 which is enclosed within the housing and which is driven by the spring motor in the usual manner, meshes with 10 a pinion gear 18 on the shaft 13. There is an opening 19 in the housing 14 which permits the pinion 18 to rotate.

A braking device cooperating with the gear 18 is provided so that the motor and toy may be 15 stopped with the motor wound up. The braking device includes a lever 20 having a gear engaging arm or brake portion 21 and a handle portion 20a which extends to the rear of the toy. The lever 20 is pivoted intermediate its ends at 22 20 to the bottom of the housing 14 and is movable in a plane intersecting the path of the gear 18. It is to be noted that the pivot 22 extends at right angles to the longitudinal axis of the gear 18 and that the lever 20 swings in a plane which passes 25 through the gear 18 longitudinally thereof. The dotted line position of the lever 20, in Fig. 2, shows it in a released position wherein the vehicle may be moved about and the motor is free to 30 actuate the rear wheels 12 through the crown gear 17 and the pinion gear 18 when the spring is wound up. The full line showing of the lever 20, in Fig. 2, shows it in locking position with the extreme end 21a thereof between two adjacent teeth 18a on the pinion 18. This is more clearly 35 shown in Fig. 3. It is to be noted that, when the lever is in locking position, the end 21a thereof engages between the teeth 18a of the pinion 18 at a point removed from the line along which the gear 17 and the pinion intermesh. Thus, it will 40 be seen that any damage which the brake lever 20 might cause to the gear 18 will not occur at the points along which the two gears intermesh so that a driving connection will always be maintained. The portion 21 of the lever 20 is slightly 45 resilient and it is to be noted that, as the lever is moved about its pivot 22 into braking position, the end 21a will frictionally engage the outer ends of the teeth 18a of the gear 18. As the gear 18 rotates, the teeth 18a will bend the end 21a of 50 the arm 21 slightly, as shown in Fig. 4, and will pass thereover. This will cause a slowing up of the gear 18 and the motor so that when the lever is moved into full locking position, the shock will 55 be greatly reduced.

The present invention, therefore, provides a braking device for a spring motor operated toy vehicle which is adapted to slow up the motor first, due to the resiliency of the arm 21, and to thereafter positively lock the motor against movement.

Of course, it is to be understood that minor changes in the details of construction and arrangement of parts may be made without departing from the spirit of the invention as set forth in the appended claims.

Having thus described the invention, what I claim as new and desire to secure by Letters Patent, is—

- 15 1. In a toy vehicle, driving wheels, a motor, intermeshing gears for providing a driving connection between said motor and said wheels, and a brake device movable into locking engagement with one of said gears at a point removed from the intermeshing portions of the gear teeth.
- 20 2. In a toy vehicle, driving wheels, a motor, intermeshing gears for providing a driving connection between said motor and said wheels, and a brake lever having an arm which is slightly resilient, said arm being movable first into fric-

tional engagement with the outer edges of the teeth of one of said gears and finally into locking engagement with the said gear at a point removed from the intermeshing portions of the gear teeth.

3. In a toy vehicle, driving wheels, a motor, 5 intermeshing gears for providing a driving connection between said motor and said wheels, and a brake lever pivotally mounted for movement in a plane passing longitudinally through one of said gears, said lever being movable into locking 10 engagement with said gear at a point removed from the intermeshing portions of the gear teeth.

4. In a toy vehicle, an axle, wheels carried by said axle, a housing, a spring motor mounted in said housing and including a driving gear, a 15 pinion gear on said axle intermeshing with said driving gear, and a lever pivotally mounted on said housing and having an arm movable in a plane passing longitudinally through said pinion gear and into positive locking engagement with 20 said pinion gear at a point removed from the intermeshing portions of the teeth of said driving gear and said pinion gear.
